Primary Examiner — Calvin E Vansant*Assistant Examiner* — Kaitlyn G Wiltshire(74) *Attorney, Agent, or Firm* — Bayramoglu Law Offices LLC(57) **CLAIM**

The ornamental design for a 3D printer frame, as shown and described.

DESCRIPTION

FIG. 1 is a perspective view of a 3D printer frame showing my new design;

FIG. 2 is a front view thereof;

FIG. 3 is a rear view thereof;

FIG. 4 is a left side view thereof, a right side view being a mirror image of the left side view;

FIG. 5 is a top view thereof; and,

FIG. 6 is a bottom view thereof.

The broken lines depict portions of the 3D printer frame that form no part of the claimed design.

1 Claim, 6 Drawing Sheets(56)
